G. TITTMANN.
PIPE SUPPORT.
APPLICATION FILED APR. 3, 1917.

1,241,683.

Patented Oct. 2, 1917.

Gotfried Tittmann
By his Attorney
Malte Verdenauer

UNITED STATES PATENT OFFICE.

GOTTFRIED TITTMANN, OF BROOKLYN, NEW YORK.

PIPE-SUPPORT.

1,241,683.

Specification of Letters Patent.

Patented Oct. 2, 1917.

Application filed April 3, 1917. Serial No. 159,589.

To all whom it may concern:

Be it known that I, GOTTFRIED TITTMANN, a citizen of the United States, and resident of Brooklyn, in the county of Kings and State of New York, have invented certain new and useful Improvements in Pipe-Supports, of which the following is a specification.

The present invention relates to attachments on smoking pipes or the like, and has for its object to provide means whereby the pipe while in use and when temporarily put away on a table, desk or the like will be supported in such a position that its mouth piece and burning end will be elevated so as not to come in contact with any article, which not only will render the use of the pipe more sanitary but also prevent damage to the table, table cloth or to articles lying near.

With this and other objects in view, my invention substantially consists of a collapsible member, removably attached to the smoking pipe which in unfolded position will support the pipe in the position mentioned and in collapsed position may serve as an ornament on the pipe.

To make my invention more clear, one form of construction is illustrated in the accompanying drawing which forms part of this specification and in which similar reference characters denote corresponding parts, Figure 1 being a side elevation of a smoking pipe and of my new attachment thereon; Fig. 2 an enlarged cross section on line 2—2 of Fig. 1 of the attachment; and Fig. 2^a a section on line 2^a—2^a of Fig. 1.

Referring specifically to the drawing, *a* denotes a smoking pipe of any well-known construction around the stem *a'* of which my new attachment is mounted. The attachment consists of a band *b* of metal or other suitable resilient material and is made in the form of a split ring so as to be capable of fitting around different sizes of smoking pipes. The band *b* is recessed or slotted as at *b'* and at its bottom is provided with a cross piece or bridge *b*² extending over the recessed portion. Suitably supported by said member *b* to be capable of swinging laterally are wings or legs *c* which are curved or bent to conform with the shape of the band *b* or circumference of the stem

of the pipe *a*, so that when the said legs or wings are collapsed or swung into inoperative position the same will be embedded in the recess *b'* on each side of the band. The free ends *c'* of these wings or legs may be curved or bent to slightly project outwardly from said recess and to form grips as indicated in dotted lines in Fig. 2. The pivotal connection of the wings *c* with the band is formed by providing the upper or inner ends of the members *c* with lateral pin or pivot-like projections *c*² which engage depressions *b*³ made at the bottom of the band *b* and in which said pins are borne. A plate spring *d* which extends below the bridge *b*² serves to hold the members *c* with their pivots *c*² in the bearings.

It will be seen that when the pipe is to be placed on a table or the like, the wings or legs *c* are turned downwardly, so as to support the pipe in the position shown in which the mouth piece *a*² and bowl will be in raised position so as not to come in contact with or burn any article near it.

In this form of construction the member is removably applied to the pipe and is made to fit various sizes of smoking pipes.

Instead of that, however, the device may be permanently attached to the pipe and be used in lieu of the ornamental silver or gold bands usually employed around the joint between the mouth piece and the stem of the pipe. The members *c* are pivotally attached to the member or band *c* in the same way as shown in Fig. 2^a.

It is of course understood that the device may be constructed in a number of other different forms without departing from the spirit of my invention, and I therefore do not wish to confine myself to the details described and shown.

What I claim and desire to secure by Letters Patent is:

1. A support for a smoking pipe, comprising a band having a recess in its bottom and a cross piece extending over said recess, members pivotally supported in said band and a spring extending between said cross piece and said members and acting on the latter.

2. A support for a smoking pipe or the like, comprising an annular band split to be adjustable for different sizes of pipes, said

band being recessed in its bottom and having a cross piece extending over the recess, members having pivotal projections engaging cavities in said band and a spring supported between said cross piece and said members and acting on the latter.

5 Signed at New York in the county of New

York and State of New York this 31st day of March, A. D. 1917.

GOTTFRIED TITTMANN.
